ATTORNEYS.

UNITED STATES PATENT OFFICE.

LAZO MARICICH, OF CHICAGO, ILLINOIS.

SWIMMING APPLIANCE.

1,221,467.

Specification of Letters Patent. Patented Apr. 3, 1917.

Application filed January 9, 1917. Serial No. 141,406.

To all whom it may concern:

Be it known that I, LAZO MARICICH, a subject of the King of Servia, residing at Chicago, in the county of Cook and State of Illinois, have invented new and useful Improvements in Swimming Appliances, of which the following is a specification.

This invention relates to swimming appliances characterized by a body harness carrying a propelling means to assist the swimming movement through the water.

The invention has for its object to provide a novel and improved appliance of the kind stated, and which is so attached to the body that the swimmer's arms and legs are left perfectly free.

With the object stated in view, the invention consists in a novel combination and arrangement of parts to be hereinafter described and claimed, and in order that the same may be better understood, reference is had to the accompanying drawing forming a part of this specification.

In the drawing,

25 Figure 1 is a perspective view of one section of the device,

Fig. 2 is an elevation of the other section, and

30 Fig. 3 is a perspective view showing a fragment of each section, as assembled.

Referring specifically to the drawing, 5 denotes an ordinary screw or other type of propeller carried by a shaft 6 provided with a bevel gear 7 which is in mesh with a bevel gear 8 provided with a sprocket wheel 9 connected by a chain 10 to a sprocket wheel 11 fast on a crank shaft 12 fitted with foot pedals 13. The propeller is therefore driven when the crank shaft is turned, the swimmer operating the said shaft by engaging the pedals with the feet in the same manner in which a bicycle is propelled.

The crank shaft 12 is carried by a frame composed of two tubes or rods 14 set closely 45 together and converging into a single tube or rod 15, the former having a suitable bearing for the crank shaft. The extremity of the tube 15 carries a spindle 16 supporting the bevel gear 8 and the sprocket wheel 9. The tube 15 also carries a tightener 17 for the chain 10. The propeller shaft 6 is supported by the tube 15.

The body harness which supports the hereinbefore described propeller and its actuating means comprises the following parts:

55 At 18 is shown a seat which may be

stamped out of sheet metal, and is shaped similar to a bicycle seat. At one end of this seat is an outstanding abdominal plate 19 hinged to the seat as shown at 20, and to the 60 other end of the seat is hinged, as shown at 21, a back plate 22. The outer end of the back plate 22 has two oppositely extending side projections 23 to each of which is loosely connected a coupling plate 24 for attachment of shoulder straps 25, and waist-encircling straps 26. The shoulder straps 25 connect at the front with tabs 27 carried by the outer end of the plate 19, the connection being an adjustable one by means of buckles 65 28. The waist straps are also made adjustable by buckles 29 and their ends are provided with suitable means for connection with the plate 19, the same being hooks 30 which are engageable with slots 31 in the 70 said plate located adjacent to the side edges thereof.

From the seat 18 depend two laterally spaced tubular bars 32 connected by cross braces 33. The outer end of each bar is 80 open and split inward from said end as shown at 34, and also has a slot 35 diametrically opposite the split. The extremity of each bar is reinforced by a clamping ring 36.

The spacing of the bars 32 conforms to the 85 spacing of the rods 14 so that the latter may be passed therewith, they being held in the bars by drawing the split ends together by means of screws 37. The portions of the rods which telescope in the bars carry screws 38 or similar laterally projecting parts seating in the slots 35, it being understood that said screws must be removed before the rods can be inserted into the bars. The parts 38 prevent loss of the propelling mechanism if 90 the connection between the same and the bars 32 should be broken in a collision or other accident.

I claim:—

1. A swimming appliance comprising a 100 seat, abdominal and back plates hinged respectively to the front and rear ends of the seat, coupling members carried on opposite sides of the back plate, waist and shoulder straps carried by the coupling members, means for connecting said straps to the abdominal plate, a supporting frame carried by the seat, and a propeller and operating means therefor carried by said supporting frame.

2. A swimming appliance comprising a 105 seat, abdominal and back plates hinged re-

110

spectively to the front and rear ends of the seat, coupling members carried on opposite sides of the back plate, waist and shoulder straps carried by the coupling members, 5 means for connecting said straps to the abdominal plate, spaced tubular bars extending from the seat, rods telescopically mounted in the outer ends of the bars, means for clamping the bars around the rods, and a 10 propeller and operating means therefor carried by the rods.

3. A swimming appliance comprising a seat, abdominal and back plates hinged respectively to the front and rear ends of the

seat, coupling members carried on opposite 15 sides of the back plate, waist and shoulder straps carried by the coupling members, means for connecting said straps to the abdominal plate, spaced tubular bars extending from the seat, rods telescopically mounted 20 in the outer ends of the bars, means for clamping the bars around the rods, said bars having slots and the rods having laterally projecting members seating in the slots, and a propeller and operating means therefor 25 carried by the rods.

In testimony whereof I affix my signature. *

LAZO MARICICH.
